 Calif., a corporation of Delaware

Application May 26, 1942, Serial No. 444,604

6 Claims. (Cl. 202—40)

The present invention relates to a process for separating a mixture of components by distillation. More particularly, it relates to a process for the separation of multi-component mixtures by distillation in the presence of a relatively high boiling selective solvent.

The present invention is applicable to the separation of relatively wide boiling range multi-component mixtures containing components of over-lapping boiling range, some of which components exhibit markedly lower vapor pressures in the presence of a relatively high boiling solvent than do other components of the mixture. Mixtures of this type are particularly apt to occur in natural products or as derivatives thereof, such as petroleum coal tar, products of the destructive distillation of wood and other vegetable or animal products and the like. Sometimes synthetic mixtures of this type also arise in manufacturing processes. Examples of such mixtures are the catalytic oxidation products of petroleum hydrocarbons such as contain acetic and propionic acids along with unoxidized hydrocarbons boiling in the range of acetic and propionic acids; products of hydrocarbon isomerization, reforming, catalytic cracking, hydrogenation, dehydrogenation, cyclization, halogenation, etc., which give rise to mixtures of compounds of neighboring boiling range but different degrees of saturation or polarity. Because these compounds have different solubilities in liquid polar solvents their vapor pressures and boiling temperatures are depressed to different extents in the presence of such liquid solvents, the compound of greatest solubility normally showing the greatest depression.

More specifically, such a mixture is illustrated by a straight run gasoline fraction having an A. S. T. M. boiling range between about 90° and 120° C. and containing benzene, toluene and saturated hydrocarbons boiling within this range. Such a mixture is considered for present purposes to be a 4-component system with benzene and toluene as the components that have relatively lower vapor pressures in the presence of a relatively high boiling polar solvent, than do the other two components comprising the saturated hydrocarbons boiling near the boiling temperature of benzene and the saturated hydrocarbons boiling near the boiling temperature of toluene.

As is well known, it is impossible to separate such a mixture into its components by ordinary fractional distillation owing to the formation of azeotropes between the saturated hydrocarbons and the aromatics, ordinary distillation being

defined as distillation in the absence of azeotrope forming agents or selective solvent for one of the components to be separated, or both. Processes have been proposed for the production of a pure component from such a mixture, for example benzene, but they have involved either very careful prefractionation to exclude high boiling components, followed by distillation in the presence of a relatively high boiling selective solvent; or else they have required a liquid phase solvent extraction treatment followed by distillation in the presence of a solvent.

It is an object of the present invention to provide an improved process for separating multi-component mixtures of the type described. It is an object to provide a process capable of separating difficultly separable multi-component mixtures of relatively wide boiling range into individual components or groups of components. Further objects will be evident from the following description.

The present invention is carried out by causing the vapor pressure relationships of the mixture to be distilled to be altered in such a sequence and manner that the formation of normally occurring azeotropes is suppressed and individual components are thus readily separated by distillation as hereinafter described.

The problem is to separate a multi-component mixture, say one containing components A, C, X and Z. In this mixture A and C, on the one hand, and X and Z, on the other, have overlapping boiling ranges, A and X normally having relatively higher vapor pressure than C and Z. However, X and Z have relatively lower vapor pressures in the presence of a relatively high boiling solvent than A and C, respectively.

The invention comprises subjecting this mixture to a continuous distillation in the presence of a relatively high boiling selective solvent under conditions to take A overhead and to remove a bottom product comprising solvent containing dissolved X, C and Z. The bottom product is separately distilled to take C and X overhead and to leave a second bottom product comprising solvent containing Z. The solvent is separated from Z by further distillation and the former is returned to the first distillation step. The overhead product comprising C and X is then distilled in the absence of any solvent, whereby they are separated from each other by virtue of their different vapor pressures.

The present invention may better be understood from a consideration of the figures. Figure I is a diagrammatic representation of the

process indicating the principle applied therein; while Figures II and III are schematic flow diagrams of different embodiments thereof.

With reference to Figure I, be it assumed that a relatively wide boiling range distillate containing components A, X, B, Y, C, and Z shall be separated into its components. Components X, Y and Z are of such nature that their vapor pressures are lower in the presence of a relatively high boiling liquid solvent than are the components A, B and C, respectively. Further, in the absence of solvent components A, B, C, and X, Y, Z have overlapping boiling ranges, i. e. the vapor pressures of A and X are closer together but are higher than those of B and Y, which likewise are close to each other and are higher than those of C and Z, the vapor pressures of the latter also being close to each other. An example of such a mixture is a straight run gasoline fraction boiling from about 60° to 150° C. Such a fraction contains aromatic hydrocarbons such as benzene corresponding to X, toluene corresponding to Y, and the xylenes and ethyl benzene corresponding to Z, and in addition saturated hydrocarbons normally having vapor pressures in the neighborhood of each of said components X, Y, Z, or else tending to form azeotropes with them. The saturated hydrocarbons may be divided into groups designated as component A, which comprises hydrocarbons having vapor pressures in the neighborhood of the vapor pressure of benzene, component B, comprising hydrocarbons having vapor pressures in the neighborhood of the vapor pressure of toluene; and component C, comprising hydrocarbons having vapor pressures in the neighborhood of the vapor pressures of xylenes and ethyl benzene. If such a mixture is distilled in the absence of solvent, an overhead mixture is first produced containing benzene (X) and saturated hydrocarbons (A) followed by toluene (Y) and saturated hydrocarbons (B), and finally the xylenes and ethyl benzene (Z) and saturated hydrocarbons (C). In other words, it is impossible to produce the various components in a pure state.

In Figure I the six components of the mixture are graphically arranged to show their mutual relationship with regard to separability.

The initial material as existing in the absence of a selective solvent is represented by state 1, wherein the horizontal lines divide the various components into pairs having normally similar vapor pressures while the vertical lines divide the components as to type, that is, by chemical constitution. Different types have different solubilities and vapor pressures in the presence of a relatively high boiling selective solvent, and thus in the presence of such a solvent the vapor pressure relationships of the components are represented by state 2, wherein components X, Y and Z all have their vapor pressures lowered with respect to the vapor pressures of A, B and C. Now, if the mixture is distilled while in this state component A may be taken overhead, and B, C, X, Y, and Z may be withdrawn with solvent as a first bottom product. This first bottom product is further distilled to take overhead B, C, X and Y, while Z is withdrawn with solvent from which it may be separated in a separate distillation step.

The mixture of B, C, X and Y, now free from or at least containing a substantially reduced amount of solvent, is represented by state 3. It is seen that A normally associated with X, and Z normally associated with C, have been removed. Consequently C and X can now be separated by

ordinary distillation in the absence of solvent. Thus, when the mixture represented by state 3 is distilled, X can be taken overhead alone while the bottom product comprising B, Y and C can be distilled in a separate step to take B and Y overhead and leave C as a bottom product. If the top product containing B and Y is now distilled in the presence of solvent, the vapor pressure relationships are represented by state 4 and upon distillation in the presence of solvent, B can be taken overhead while solvent and Y can be taken off as a bottom product from which Y can be separated.

Figure II is a flow diagram representing a continuous distillation for separating pure components A, X, B, Y, C and Z from a feed mixture containing them, in accordance with the scheme of Figure I. The feed mixture comprising components A, X, B, Y, C and Z is continuously fed via line 4 to extractive distillation column 2 equipped with reboiler 3. Herein the feed is distilled in the presence of a relatively high boiling solvent which is admitted to column 2 via line 4 and flows down the column countercurrently to ascending vapors. Vapors of A pass overhead via line 5 and are condensed in condenser 6 and collect in accumulator 7, whence a portion of the condensed product A is returned to column 3 as reflux via line 8, while the remainder passes to storage not shown via line 9.

From the bottom of column 2 are withdrawn through line 10 components X, B, Y, C and Z, and solvent, which pass to extractive distillation column 11 equipped with reboiler 12. Vapors comprising X, B, Y and C are taken overhead via line 13 to condenser 14 and condensed vapors collect in accumulator 15, whence a portion of condensed vapors may be returned to column 11 as reflux via line 16 while the remaining portion passes to column 27 to be treated as described subsequently.

From the bottom of column 11 is withdrawn solvent containing dissolved Z through line 17 and passes to solvent recovery column 18 equipped with reboiler 19. Herein component Z is stripped from solvent, which latter is withdrawn from column 18 via line 4 and recycled to column 2 to contact further quantities of feed. A portion of the recycled lean solvent may be returned to column 11 via valved line 20 to aid in the separation of X, B, Y and C from solvent and Z therein, if desired. Vapors of Z pass overhead from column 18 through line 21 to condenser 22 and accumulator 23, whence a portion of component Z is returned to column 18 as reflux via line 24, while the remainder passes to storage not shown via line 25.

The top product from column 11 containing X, B, Y and C passes via line 26 to fractionating column 27 equipped with reboiler 28. Herein X is separated from B, Y and C, X passing overhead via line 28 to condenser 29. Condensed vapors collect in accumulator 30, whence a portion is returned to column 27 as reflux via line 31, while the remainder passes to storage not shown via line 32. The latter product comprising B, Y and C is withdrawn via line 33 and passes to fractionating column 34 equipped with reboiler 35. Herein the B and Y are taken overhead, while C is withdrawn as bottom product via line 36 and passes to storage not shown. Vapors of B and Y pass overhead via line 37 to condenser 38. Condensed vapors collect in accumulator 39 whence a portion is returned to column 34 as reflux via line 40, while the remainder

passes via line 41 to extractive distillation column 42 equipped with reboiler 43. Herein B and Y are distilled in the presence of solvent admitted to column 42 via line 44. Vapors of B pass overhead via line 45 to condenser 46. Condensed B collects in accumulator 47, whence a portion is returned to column 42 as reflux via line 48, while the remainder passes to storage not shown via line 49.

From the bottom of column 42 solvent and Y are withdrawn and pass via line 50 to solvent recovery column 51 equipped with reboiler 52. Lean solvent is withdrawn from the bottom of column 51 and recycled to column 42 via line 44. Vapors of Y pass overhead via line 53 to condenser 54. Condensed Y collects in accumulator 55 whence a portion is returned to column 51 as reflux via line 56 while the remainder is withdrawn via line 57 and passes to storage not shown. Make-up quantities of solvent may be added to the cycle via valved lines 58 and 59.

Figure III is a flow diagram representing another embodiment of the present invention which is particularly suitable for the separation of a four-component system of the nature described, because in this case it is possible to effect the separation of the components in a pure condition with but four distillation columns. A feed comprising A, X, C and Z is continuously fed via line 101 to extractive distillation column 102 equipped with reboiler 103. Herein the mixture is distilled in the presence of a relatively high boiling solvent which is admitted to column 102 via line 104, which flows down the column countercurrently to ascending vapors as the distillation proceeds. Vapors comprising A are taken overhead via line 105 and pass to condenser 106. Condensed vapors collect in accumulator 107 whence a portion may be returned to column 102 via line 108 as reflux, while the remainder is withdrawn through line 109 and passes to storage not shown. From the bottom of column 102 is withdrawn the solvent with components X, C and Z, which pass via line 110 to extractive distillation column 111 equipped with reboiler 112. This column is operated in such a manner as to take overhead components X and C, while withdrawing a bottom product through line 113 comprising solvent and Z, which latter product passes via line 113 to solvent recovery column 114 equipped with reboiler 115. Lean solvent is withdrawn from column 114 which is recycled to column 102 via line 104. If desired, a portion of lean solvent may be returned to column 111 via valved line 116 to aid in the separation of X and C from solvent and Z. Overhead product from column 114 comprises vapors of Z, which pass through line 117 to condenser 118. Condensed vapors collect in accumulator 119, whence a portion is returned to column 114 as reflux via line 120, while the remainder passes to storage not shown via line 121.

The overhead vapors from column 111 comprising X and C pass via line 122 to condenser 123. Condensed vapors collect in accumulator 124 whence a portion is returned to column 111 as reflux while the remainder passes via line 126 to fractionating column 127, equipped with reboiler 128, which is operated in such a manner as to take overhead component X via line 129 to condenser 130. Condensed vapors of X collect in accumulator 131, whence a portion is returned to column 127 as reflux via line 132, while the remainder is withdrawn and passes to storage not shown via line 133. Component C is withdrawn

from the bottom of column 128 via line 134. Make-up quantities of solvent may be added to the system via valved line 135.

In the flow diagrams pumps, heat exchangers, valves, flow control equipment, and other auxiliaries, the proper placement of which is evident to one skilled in the art, have been omitted.

From the foregoing it is evident that the present invention is applicable to the separation of

10 any multi-component mixture of overlapping boiling range provided a solvent exists in which the vapor pressure of some of the components is reduced to a greater degree than that of the other components.

15 In general, solvents reduce the vapor pressure of the more soluble components to a greater degree than the less soluble components, and further, in general, the solvent will tend to depress more the vapor pressure of the components more closely chemically (structurally) related thereto.

20 In separating hydrocarbons of different degrees of saturation various polar solvents may be em-

ployed, e. g. phenol, cresylic acids, alkyl phenol mixtures, aniline, alkyl anilines, diphenyl amine, ditolyl amines, carbitols (diethylene glycol mono-

25 ethers) such as methyl, ethyl, propyl, carbitols; chlorinated dialkyl ethers such as beta-beta-dichlorethyl ether, nitrobenzene, nitrotoluene, nitroxylenes, naphthols, alkyl naphthols, benzo-

30 phenone, phenyl tolyl ketone, diphenylene ketone; alkyl phthalates, such as dimethyl phthalate; alkyl salicylates such as methyl salicylate;

35 benzyl alcohol, benz chlorides, i. e. benzyl, benzal, benzo chlorides, benzonitrile, diphenyl oxide, ditolyl oxide, hydroxy pyridine, nitropyridine, chlorinated pyridines, quinoline, isoquinoline, chlorinated quinoline, hydroxy quinolines, 5-nitro quinoline, tetra-hydrofurfuryl alcohol, furfural alcohol, furfural; the monoglycerol ethers such

40 as 1-methoxy glycerol, 2-methoxy glycerol, 1-

ethoxy glycerol, 2-ethoxy glycerol, 1-propoxy glycerol, 2-propoxy glycerol, 1-isopropoxy glycerol, 2-isopropoxy glycerol; the glycerol di-ethers such as 1,2-dimethoxy glycerol, 1,3-dimethoxy

45 glycerol, 1,2-diethoxy glycerol, 1,3-diethoxy glycerol, 1,2-dipropoxy glycerol, 1,3-dipropoxy glycerol, 1,2-di-isopropoxy glycerol, and 1,3-di-isopropoxy glycerol; the mixed diglycerol ether esters such as 1-ethoxy,2-methoxy glycerol, 1-

50 methoxy,3-propoxy glycerol, 1-ethoxy,2-isopropoxy glycerol; acetone or acetone-water mixture, dioxane, acetonitrile, etc.

Suitable solvents should have high enough boiling temperatures that they may be separated 55 from the dissolved components without the necessity of employing an excessively large number of plates or high reflux ratios. It is preferable to employ solvents which are relatively stable under the distillation conditions in the presence of the substance to be separated.

60 I claim as my invention:

1. A process for separating a mixture comprising a first pair of components A and X and a second pair of components C and Z, the components of said first pair normally having vapor pressures higher than the vapor pressures of the components of said second pair, said components X and Z having relatively lower vapor pressures in the presence of a substantial concentration of

70 a relatively high boiling selective solvent than said components A and C respectively, comprising the steps of fractionally distilling said mixture in the presence of a substantial concentration of said solvent under conditions to form a first overhead product rich in said component A

and leave a first bottom product comprising said solvent and said components C, X and Z, further distilling said first bottom product under conditions to form a second overhead product rich in said components C and X and leave a second bottom product comprising said solvent and Z, further distilling at least a portion of said second bottom product under conditions to separate said solvent and Z, recycling at least a portion of the resulting separated solvent to said first mentioned distillation step, and further distilling at least a portion of said second overhead product with substantially reduced concentration of solvent to separate said components C and X.

2. The process of claim 1 wherein said mixture is a hydrocarbon mixture comprising benzene and toluene and non-aromatic hydrocarbons, said benzene corresponding to component X, said toluene corresponding to component Z, the hydrocarbons boiling near the boiling temperature of benzene comprising component A, the hydrocarbons boiling near the boiling temperature of toluene comprising component C, and said solvent comprising a relatively higher boiling polar solvent.

3. The process of claim 1 wherein said mixture is a hydrocarbon mixture comprising toluene and the xylenes and ethyl benzene, and non-aromatic hydrocarbons, said toluene corresponding to component X, said xylenes and ethyl benzene corresponding to component Z, the hydrocarbons boiling near the boiling temperature of toluene comprising component A, the hydrocarbons boiling near the boiling temperature of the xylenes and ethyl benzene comprising component C, and said solvent comprising a relatively higher boiling polar solvent.

4. A process for separating a mixture comprising a first pair of components A and X and a second pair of components C and Z, the components within each of said pairs having such similar vapor pressures as to make their separation difficult by ordinary fractional distillation but the components of said first pair normally having vapor pressures higher than the vapor pressures of the components of said second pair, said components X and Z having relatively lower vapor pressures in the presence of a substantial concentration of a relatively high boiling selective solvent than said components A and C respectively, comprising the steps of fractionally distilling said mixture in the presence of a substantial concentration of said solvent under conditions to form a first overhead product rich in said component A and leave a first bottom product comprising said solvent and said components C, X and Z, and further distilling said first bottom product under conditions to form a second overhead product rich in said components C and X and leave a second bottom product comprising said solvent and Z, further distilling at least a portion of said second bottom product under conditions to separate said solvent and Z, recycling at least a portion of the resulting separated solvent to said first mentioned distillation step, and further distilling at least a portion of said second overhead product substantially in the absence of solvent to separate said components C and X.

5. A process for separating a mixture compris-

ing a first pair of components A and X and a second pair of components C and Z, the components of said first pair normally having vapor pressures higher than the vapor pressures of 5 the components of said second pair, said components X and Z having relatively lower vapor pressures in the presence of a substantial concentration of a relatively high boiling selective solvent than said components A and C respectively, comprising the steps of fractionally distilling said mixture in the presence of a substantial concentration of said solvent under conditions to take overhead substantially pure component A and leave a first bottom product comprising said solvent and said components C, X and Z, further distilling said first bottom product under conditions to form a second overhead product comprising components C and X and to leave the second bottom product consisting of 10 said solvent and component Z substantially free from said components A, C and X, further distilling at least a portion of said second bottom product under conditions to separate said solvent and component Z, recycling at least a portion of the resulting separated solvent to said 15 first distillation step, and further distilling at least a portion of said second overhead product substantially in the absence of solvent to separate components C and X.

6. A process for separating a mixture comprising a first pair of components A and X, a second pair of components B and Y, and a third pair of components C and Z, the components of said first pair normally having vapor 20 pressures higher than the vapor pressures of the components of said second pair which latter normally have vapor pressures higher than the components of said third pair, said components X, Y and Z having relatively lower vapor 25 pressures in the presence of a substantial concentration of a relatively high boiling selective solvent than said components A, B and C respectively, comprising the steps of fractionally distilling said mixture in the presence of a substantial concentration of said solvent under conditions to form a first overhead product rich in 30 said component A and leave a first bottom product comprising said solvent and said components B, C, X, Y and Z, further distilling said 35 first bottom product under conditions to form a second overhead product rich in said components B, C, X and Y and leave a second bottom product comprising said solvent and Z, further 40 distilling at least a portion of said second bottom product to separate component Z from said solvent and recycling at least a portion of the resulting separated solvent to said first distillation step, further distilling said second overhead product in the presence of a substantially reduced 45 concentration of solvent under conditions to produce third top and bottom products rich in said components X and C respectively, and produce an intermediate fraction comprising said components B and Y, and further distilling said 50 intermediate product in the presence of a substantial concentration of a relatively high boiling selective solvent to separate said components B and Y.

EMMETT L. DURRUM.
